CABINET PULL OR SIMILAR ARTICLE

Dean W. Myers and Luis E. Smith, Newport Beach, Calif.,
assignors to Jaybee Manufacturing Corp., Los Angeles,
Calif., a corporation of California

Filed June 3, 1963, Ser. No. 75,184

Term of patent 14 years

(Cl. D10—8)

FIG. 1.

FIG. 2.

FIG. 3.

FIG. 4.

FIG. 5.

FIG. 6.

FIGURE 1 is a front elevational view of a cabinet pull incorporating our invention in which the characteristic biconcave design element is of light color or bright finish on a contrasting background;

FIG. 2 is a side elevational view thereof;

FIG. 3 is an end elevational view thereof;

FIG. 4 is an enlarged fragmentary sectional view taken along a plane corresponding to line 4—4 of FIG. 1;

FIG. 5 is an enlarged sectional view taken along a plane corresponding to line 5—5 of FIG. 1; and

FIG. 6 is a front elevational view similar to FIG. 1 of a modified cabinet pull in which the characteristic biconcave design element contrasts with a light color or bright finish background.

We claim:

The ornamental design for a cabinet pull or similar article, substantially as shown and described.
